TOY BALLOON MERCURY CAPSULE

Robert A. Wolfe, 455 Elizabeth Ave., Newark, N.J.

Filed Apr. 17, 1964, Ser. No. 79,540

Term of patent 14 years

(Cl. D34—15)

FIG. 1 is a front elevation of a toy balloon mercury capsule showing my new design;

FIG. 2 is a rear elevational view of the toy balloon mercury capsule of FIG. 1; and

FIG. 3 is a side elevational view of the toy balloon mercury capsule of FIGS. 1 and 2.

The dominant features of my design reside in the portions shown in full lines.

I claim:

The ornamental design for a toy balloon mercury capsule, as shown and described.
